STOP MOTION FOR WEFT REPLENISHING LOOMS

Walter H. Wakefield, Worcester, Mass., assignor to Crompton & Knowles Loom Works, Worcester, Mass., a corporation of Massachusetts

Application May 19, 1948, Serial No. 27,898

16 Claims. (Cl. 139—290)

1

This invention relates to improvements in weft replenishing looms and it is the general object of the invention to provide means for stopping the loom if the picker is worn so badly that it permits the shuttle to box too deeply for a proper bobbin transfer.

In weft replenishing looms an initiated bobbin transferring operation is completed if the shuttle is boxed beyond a given point on the lay but is revoked if the shuttle is insufficiently boxed and projects inwardly from the point toward the center of the loom. If the picker should become badly worn the shuttle can pass beyond the aforesaid point and be boxed so deeply that the butt of the incoming bobbin will be forced down against a solid part of the shuttle with resultant breakage. Weft replenishing looms are not ordinarily provided with any means for taking care of this latter condition, and it is an important object of the present invention to provide means by which the loom will be stopped if the shuttle is too deeply boxed for transfer and has passed beyond registry with the bobbin in transfer position.

It is another object of the present invention to provide an auxiliary shuttle feeler controlled by the primary shuttle feeler for effecting the aforesaid loom stoppage. The auxiliary shuttle feeler set forth hereinafter operates in a manner the opposite of that of the usual shuttle feeler in that a shuttle properly placed for transfer will engage the auxiliary feeler and prevent it from acting to change loom operation.

A shuttle may be in any one of three positions when a replenishing operation is called. It may be correctly placed, in which event transfer should be permitted to proceed normally, it may be insufficiently boxed, in which event transfer should be revoked, or it may be too deeply boxed to receive a bobbin, and the loom should be stopped. It is a further object of the invention to provide shuttle position detecting means which will effect appropriate control of the loom when the shuttle is in any one of the three positions mentioned.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation partly in section of a loom having the present invention applied thereto.

Fig. 2 is an enlarged side elevation of part of

2

the structure shown in Fig. 1, parts being in section, showing the auxiliary shuttle feeler in detecting position preparatory to a weft replenishing operation of the loom and showing the lay in two positions,

Fig. 3 is a plan view looking in the direction of arrow 3, Fig. 2,

Fig. 4 is a vertical enlarged section on line 4—4 of Fig. 2,

Fig. 5 is a side elevation partly in section showing the manner in which the auxiliary shuttle feeler is reset,

Fig. 6 is a plan view of the shuttle box and associated shuttle picking mechanism, and

Fig. 7 is a diagrammatic view of an electric circuit which can be used with the invention.

Referring particularly to Figs. 1 and 2, the loom frame 10 supports a reciprocating lay 11 carrying a shuttle box 12 which receives a shuttle S. A dagger 13 on the lay is provided for engagement with a transerrer latch 14 mounted on a bobbin transerrer arm 15 pivotally mounted on a fixed stud 16. The latch 14 is normally down below the position shown in Fig. 1, but when a weft replenishing operation is called by depletion of weft the latch is raised by a rod 17.

The magazine M is shown as of the stationary multi-stack type and supports a reserve bobbin B in transfer position under transerrer arm 15 when a replenishing operation is to occur. The magazine is provided with a fixed stud 20 pivotally supporting hub 21 of a casting 22 formed with two arms 23 and 24, see Figs. 2 and 3. An upwardly extending rod 25 is attached to arm 24 and determines the vertical position of a primary shuttle position detector or shuttle feeler 26 of usual form secured to arm 23. Ordinarily rod 25 is in its raised position and the shuttle feeler 26 is in its normal non-detecting elevated position so a lay carried element, such as the back wall 27 of the shuttle box, passes under the shuttle feeler without striking it. When a replenishing operation is called rod 25 descends at the same time rod 17 rises and lowers the shuttle feeler to the detecting position shown in Fig. 2. If the shuttle is insufficiently boxed it engages and raises the shuttle feeler 26 and raises rod 25 to revoke the transfer, otherwise transfer proceeds in usual manner and the shuttle feeler is later raised by the box back 27.

For the purposes of this description arm 23 and shuttle feeler 26 may be considered the primary shuttle feeler.

The shipper and brake handles 30 and 31, respectively, operate in usual manner and when

moved forwardly, or to the left as viewed in Fig. 1, rock a shipper lever 32 counter-clockwise as viewed in Fig. 1 to exert forward pulls on rods 33 and 34 the effect of which is to take the brake off and throw the loom clutch into driving position. An arm 35 extending downwardly from the brake lever 31 has pivoted thereto a knock-off or stopping latch 36 held normally in raised position by a light coil spring 37 the upper end of which is fixed as at 38. A rod 39 depends from the knock-off latch 36 and is connected to the core 40 of a normally deenergized stationary but vertically adjustable solenoid 41.

A knock-off dagger 42 on the lay ordinarily passes under the latch 36, but when the latter is pulled down against the action of spring 37 due to energization of solenoid 41, dagger 42 engages the latch 36 and rocks the brake handle to the right as viewed in Fig. 1 to stopping position. A thrust screw 43 on the shipper handle is pushed rearwardly by the brake handle and causes the shipper lever 30 to move to stopping position along with the brake lever 31.

The matter thus far described is of known construction and operates in the usual manner and except as pointed out hereinafter forms no part of the present invention. Reference may be had to Darwin Patent No. 2,263,983 for further description of latch 36 and the parts associated therewith.

The shuttle S is picked from the shuttle box by a picker 45, see Fig. 6, slideable along a lay carried picker spindle 46 by means of power derived from a picker stick 47. The end of the lay is formed with a wall 48 along the inner side of which is located a bunter 49 which may be formed of several folds of leather or other resilient material. This bunter is in contact with the head 50 of the picker which engages the shuttle, and the bunter is so mounted that it can be moved to the left as viewed in Fig. 6 to permit the addition of shims between it and wall 48 to move the shuttle toward the longitudinal center of the shuttle box as the picker wears.

In the course of loom operation the head 50 of the picker is subjected to considerable wear and the socket in it which receives the tip end 52 of the shuttle may increase in size to such an extent that the shuttle will enter the shuttle box too far for a proper replenishing operation. As shown in full lines in Fig. 6 the shuttle is properly placed to receive the reserve bobbin B, Fig. 1, when it is pushed down out of the magazine into the shuttle by the transfer arm 15. Under these conditions the inner or left end of the shuttle as viewed in Fig. 6 will clear the shuttle feeler arm 26 as the lay moves forwardly from the full to the dotted line position of Fig. 2 and the initiated replenishing operation can be completed. If the excessive wear of the picker head 50 should permit the shuttle to box too deeply and assume the dotted line position shown in Fig. 6 the butt of the incoming bobbin will be over a solid part of the shuttle, such as that indicated at 55, and will not be able to enter the holding spring clips 56 of the shuttle. Under these conditions it is desirable to stop the loom so that the picker can either be replaced or shims or the like be placed between the bunter 49 and wall 48 so that the picker 45 can come to rest in the full line position shown in Fig. 6.

In carrying the invention into effect I provide an auxiliary or secondary shuttle position detector or shuttle feeler 60 pivoted as at 61 to arm 23 of casting 22. A spring plunger 62 on arm 23

enters a shallow notch 63 on the auxiliary feeler 60 to hold the same yieldingly in normal position with both the primary and auxiliary shuttle feelers normally aligned as indicated for instance in Fig. 2.

The auxiliary shuttle feeler 60 has mounted thereon a loom controller in the form of an electric switch 65 having an arm 66 extending downwardly and forwardly, or to the right as viewed in Fig. 2. Switch 65 is normally open and solenoid 41 will normally be deenergized, see Fig. 7, but when switch 65 is closed the solenoid will be energized.

Under normal conditions both shuttle feelers 26 and 60 will be in raised non-detecting position, but upon initiation of a weft replenishing operation both feelers will be lowered to detecting position due to descent of rod 25. Under this condition the shuttle feeler 60 and switch 65 are in controlling or stopping position. If the shuttle is not sufficiently boxed the usual or primary shuttle feeler 26 will be raised by the misplaced shuttle as the lay advances and transfer will be prevented or revoked. If, on the other hand, the shuttle is in the dotted line position of Fig. 3 and is correctly placed for transfer it will advance to one side of the shuttle feeler 26 and the latter will remain down, thereby permitting completion of the initiated replenishing operation.

When the shuttle is in the dotted line position of Fig. 3 it will raise the auxiliary shuttle feeler 60 at a given point in the cycle of the loom as the lay advances before the box back 27 engages arm 66 of switch 65. The latter will therefore be moved away from its stopping or controlling position and remain open as shuttle feeler 60 rises and the solenoid will not be energized. If, however, the shuttle should be too deeply boxed for correct transfer due to an excessively worn picker and assume the dot and dash line position shown in Fig. 3 it will not engage the auxiliary feeler and the latter will remain down subsequent to said point in the loom cycle so that the advancing shuttle box back 27 will engage arm 66 and close the switch 65. This will close the circuit shown in Fig. 7 to energize the solenoid and move stop latch 36 into the path of the advancing stopping bunter 42 to effect rocking of the shipper and brake handles as already described to stop the loom. The auxiliary feeler 60 is preferably set so that it will effect loom stoppage before wearing of the picker will permit such deep boxing of the shuttle as will result in breakage at the time of transfer.

Under normal conditions of transfer the auxiliary shuttle feeler 60 will be raised with respect to the primary shuttle feeler 26 and spring plunger 62 will move out of pocket 63. This upward movement of feeler 60 will occur while shuttle feeler 26 is still down, and it is necessary to restore the normal relation of the two shuttle feelers.

As the lay approaches front center position during a normal replenishing operation the box back 27 will engage the primary shuttle feeler 26 and raise it to reset the magazine. During this upward movement of the primary shuttle feeler the auxiliary feeler will be moved against a resetting stop 70, see Figs. 2 and 5, so that as the shuttle feeler 26 returns to its normal reset position it will rise relatively to the auxiliary shuttle feeler and will eventually restore the normal positions of the two feelers. This restoration may be effected either entirely by action of stop 70, or partly by action of the stop and

partly by camming action of the spring plunger as it reenters the recess or notch 63. In either event both shuttle feelers will be returned to their normal position upon completion of a replenishing operation.

It should also be noted that the feelers will be reset if both are engaged by a misplaced shuttle. Resetting will also occur even though the auxiliary shuttle feeler should be missed by a shuttle which is too deeply boxed. This is because of the fact that under these conditions spring of plunger 62 will lift feeler 60 when feeler 26 is raised.

From the foregoing it will be seen that I have provided simple means by which loom operation can be controlled due to the position of the shuttle on replenishing beats of the loom, and wherein a shuttle which is too deeply boxed for proper transfer and has passed beyond registry with the bobbin in transfer position will cause closure of switch 65 by box back 27 to effect loom stoppage. The auxiliary feeler is controlled by the usual mechanism which places the primary shuttle feeler in shuttle detecting position preparatory to a replenishing operation, and both shuttle feelers are returned to normal position after initiation of a replenishing operation whether the primary shuttle feeler be engaged by a misplaced shuttle, whether the replenishing operation proceeds normally or whether the auxiliary shuttle feeler is not engaged by the shuttle but is raised by the primary feeler due to action of spring plunger 62. The shuttle can be insufficiently boxed, correctly boxed, or too deeply boxed for transfer, and the shuttle feelers will act accordingly to exercise the appropriate control over the loom.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom in which a shuttle to be replenished may be correctly boxed for bobbin transfer, or be insufficiently boxed or too deeply boxed for correct bobbin transfer, shuttle position detecting means including primary and auxiliary shuttle feelers normally in non-detecting position but moved to detecting position preparatory to a weft replenishing operation, the primary shuttle feeler revoking the replenishing operation if the shuttle is insufficiently boxed, and means controlled by the auxiliary shuttle feeler to stop the loom if the shuttle is too deeply boxed, said shuttle feelers being ineffective to revoke the replenishing operation or effect loom stoppage if the shuttle is correctly boxed.

2. In a weft replenishing loom in which a shuttle to be replenished may be too deeply boxed for correct bobbin transfer, a shuttle position feeler normally in non-detecting position but moved to shuttle detecting position preparatory to a weft replenishing operation, and loom controlling means including a part controlled by the shuttle feeler effective to stop the loom if the shuttle is too deeply boxed to engage the shuttle feeler.

3. In a weft replenishing loom in which a shuttle to be replenished may be correctly boxed for bobbin transfer or be too deeply boxed for correct bobbin transfer, a lay moving the shuttle forwardly on a weft replenishing beat of the loom, a shuttle position feeler in shuttle detecting position on a weft replenishing beat, means controlled

by the shuttle feeler and operated by the lay to effect stoppage of the loom if the shuttle is too deeply boxed for correct transfer, said shuttle feeler being positioned to be engaged by the shuttle if the latter is correctly boxed and moved by the shuttle to prevent said means from being operated by the lay.

4. In a weft replenishing loom in which a lay carried shuttle to be replenished by a reserve bobbin may be correctly boxed for bobbin transfer or be too deeply boxed for correct bobbin transfer, a shuttle position detector normally in non-detecting position but moved to detecting position on a replenishing beat of the loom, an electric switch on said detector moved into the path of the lay when the detector moves to detecting position, and electric means effective to stop the loom when the switch is closed, the shuttle if correctly boxed for bobbin transfer engaging said

15 shuttle feeler as the lay advances and moving the shuttle feeler to move the switch to a position in which it cannot be closed by the lay, and the shuttle feeler in the event the shuttle is too deeply boxed to engage the shuttle feeler holding the switch in position to be closed by the lay.

5. In a weft replenishing loom having a lay and a shuttle on the lay which at the time of a weft replenishing operation of the loom may be correctly boxed for bobbin transfer or may be too deeply boxed for transfer, a shuttle position detector normally in non-detecting position out of the path of the lay but moved to detecting position preparatory to a weft replenishing operation of the loom, a normally open electric switch on the shuttle position detector, means effective upon closure of the switch to effect loom stoppage, and an element on the lay for operation of the switch, the shuttle when correctly boxed engaging the shuttle position detector to move the

20 latter to move the switch out of the path of said element, the shuttle position detector in the event that the shuttle is too deeply boxed for correct transfer remaining in detecting position to effect closure of the switch by said element.

45 6. In a weft replenishing loom having a lay provided with a shuttle which may be correctly boxed for bobbin transfer on a weft replenishing beat of the loom, or may be insufficiently boxed or too deeply boxed for correct bobbin transfer,

50 a primary shuttle position detector normally in non-detecting position but moving to shuttle position detecting position incident to a weft replenishing operation of the loom and effective to prevent the weft replenishing operation if the 55 shuttle is insufficiently boxed, a second shuttle position detector mounted on the primary detector and moving to detecting position when the primary detector moves to detecting position, the secondary detector being engaged and moved by the shuttle when the latter is correctly positioned for transfer but being unmoved by the shuttle if the latter is too deeply boxed for correct bobbin transfer, and means effective to stop the loom in the event that the secondary detector

60 by the shuttle when the latter is correctly positioned for transfer but being unmoved by the shuttle if the latter is too deeply boxed for correct bobbin transfer, and means effective to stop the loom in the event that the secondary detector 65 remains unmoved by the shuttle due to the fact that the latter is too deeply boxed.

7. In a weft replenishing loom having a lay operating with a shuttle which on a weft replenishing beat of the loom may occupy three 70 different positions in the first of which the shuttle is insufficiently boxed for transfer, in the second of which the shuttle is correctly boxed for transfer, and in the third of which the shuttle is too deeply boxed for correct transfer, and shuttle 75 position detector means normally in non-detect-

ing position but moved to detecting position preparatory to a weft replenishing operation and effective to prevent the weft replenishing operation if the shuttle is in the first of said positions, permit the weft replenishing operation if the shuttle is in the second of said positions, and stop the loom if the shuttle is in the third of said positions.

8. In a weft replenishing loom having a lay provided with a shuttle which may be insufficiently boxed for a bobbin transfer, correctly boxed for a bobbin transfer, or too deeply boxed for a correct bobbin transfer, a primary shuttle feeler, a secondary shuttle feeler pivoted on the primary feeler, both of said shuttle feelers being normally in a given position relatively to each other and normally in non-detecting position and both moved to detecting position preparatory to a weft replenishing operation of the loom, the primary feeler being moved away from the detecting position thereof when the shuttle is insufficiently boxed and effecting movement of the secondary shuttle feeler away from the detecting position thereof, said primary shuttle feeler remaining in detecting position if the shuttle is correctly boxed, the shuttle when correctly boxed engaging the secondary shuttle feeler to move the latter with respect to the primary shuttle feeler but remaining in detecting position if the shuttle is too deeply boxed for correct transfer, and means effecting loom stoppage if the secondary shuttle feeler remains in detecting position due to the fact that the shuttle is too deeply boxed.

9. In a weft replenishing loom having a lay provided with a shuttle which may be insufficiently boxed for a bobbin transfer, correctly boxed for a correct bobbin transfer, a primary shuttle feeler, a secondary shuttle feeler pivoted on the primary feeler, both of said shuttle feelers being normally in a given position relatively to each other and normally in non-detecting position and both moved to detecting position preparatory to a weft replenishing operation of the loom, the primary feeler being moved away from the detecting position thereof when the shuttle is insufficiently boxed and effecting movement of the secondary shuttle feeler away from the detecting position thereof, said primary shuttle feeler remaining in detecting position if the shuttle is correctly boxed, the shuttle when correctly boxed engaging the secondary shuttle feeler to move the latter with respect to the primary shuttle feeler but remaining in detecting position if the shuttle is too deeply boxed for correct transfer, means effecting loom stoppage if the secondary shuttle feeler remains in detecting position due to the fact that the shuttle is too deeply boxed, and means operating due to movement of the primary shuttle feeler from the detecting position thereof back to the normal non-detecting position thereof to reset the secondary shuttle feeler to said given normal position relatively to the primary shuttle feeler.

10. In a weft replenishing loom having a shuttle to be replenished, said shuttle capable of being insufficiently boxed for a correct bobbin transfer, correctly boxed for a correct transfer, or too deeply boxed for correct transfer, shuttle position detecting means including two shuttle feelers movable independently of each other and spaced in the direction of the length of the shuttle, one of said shuttle feelers in the event the shuttle is insufficiently boxed preventing the weft

replenishing operation and means controlled by the other shuttle feeler in the event the shuttle is too deeply boxed to effect loom stoppage, both of said shuttle feelers in the event the shuttle is properly placed permitting completion of the weft replenishing operation without revoking the latter or stopping the loom.

11. In a weft replenishing loom in which a shuttle to be replenished may be correctly boxed for bobbin transfer or be too deeply boxed for correct transfer, a shuttle position detector positioned on a replenishing beat of the loom to be engaged by the shuttle if the latter is correctly boxed for bobbin transfer, and means including a loom controller moved by the shuttle feeler effective to stop the loom if the shuttle is too deeply boxed to engage the shuttle feeler.

12. In a weft replenishing loom in which a shuttle to be replenished with a reserve bobbin may be correctly boxed to receive the bobbin or may be too deeply boxed for correct reception of the bobbin, a shuttle feeler in shuttle position detecting position on a replenishing beat of the loom engaged and moved by the shuttle if the latter is correctly boxed but unengaged by the shuttle if the latter is too deeply boxed for correct reception of the bobbin, loom controlling means moving with the shuttle feeler and located in stopping position when the shuttle feeler is in detecting position and remaining in stopping position if the shuttle does not engage the shuttle feeler, but moving to non-stopping position if the shuttle engages the shuttle feeler, and means to stop the loom if the controller remains in stopping position.

13. In a weft replenishing loom in which the shuttle to be replenished moves forwardly with the lay and may be correctly boxed for a replenishing operation or may be too deeply boxed for a correct replenishing operation, a movable shuttle feeler in stopping position in the path of forward movement of the lay and also in the path of forward movement of the shuttle if the latter is correctly boxed, and a loom controller on the shuttle feeler in the path of the lay for cooperation therewith to effect loom stoppage if the shuttle feeler remains in stopping position, the shuttle feeler being engaged by the shuttle and moved thereby away from stopping position if the shuttle is correctly boxed but remaining in stopping position if the shuttle is too deeply boxed to engage the shuttle feeler.

14. In a weft replenishing loom in which a shuttle to be replenished may be too deeply boxed for correct bobbin transfer, a shuttle position feeler normally in non-detecting position but moved to shuttle detecting position preparatory to a weft replenishing operation, and electric loom controlling means including an electric switch on the shuttle feeler effective to stop the loom if the shuttle is too deeply boxed to engage the shuttle feeler.

15. In a weft replenishing loom in which a shuttle to be replenished may be correctly boxed for bobbin transfer or be too deeply boxed for correct bobbin transfer, a lay moving the shuttle forwardly on a weft replenishing beat of the loom, a shuttle position feeler normally in non-detecting position but moved to detecting position preparatory to a weft replenishing operation of the loom, a loom controller moved from non-controlling position to controlling position in the path of the lay by the shuttle feeler when the latter moves to detecting position, the shuttle if correctly boxed engaging the shuttle feeler and

thereby effecting movement of the controller out of the path of the lay, and the shuttle if too deeply boxed failing to engage the shuttle feeler and failing to effect movement of the controller out of the path of the lay, whereupon the controller is engaged by the lay, and means controlled by the controller effecting a change in loom operation when the lay engages said controller.

16. In a weft replenishing loom in which a shuttle to be replenished may be correctly boxed for bobbin transfer or too deeply boxed for correct bobbin transfer, a shuttle position feeler normally in non-detecting position but moved to detecting position with respect to the shuttle preparatory to a weft replenishing operation of the loom, a loom controller normally in non-controlling posi-

15

tion but moved to controlling position by the shuttle feeler when the latter moves to detecting position, the shuttle if correctly boxed engaging the shuttle feeler and effecting movement of the controller away from detecting position at a given point in the cycle of the loom, the shuttle if too deeply boxed for correct bobbin transfer failing to engage the shuttle feeler, whereupon the controller remains in controlling position subsequent to said given point in the loom cycle, and means under control of the controller effecting a change in loom operation if the controller remains in the controlling position thereof subsequent to said point in the loom cycle.
